GRINDING AND POLISHING MACHINE

Friedrich Zeissl, Heilbronn-Bockingen, Germany

Application July 7, 1936, Serial No. 89,369
In Germany July 10, 1935

8 Claims. (Cl. 51—100)

This invention relates to an improved machine for automatically grinding and polishing especially elongated or extended articles of any material and any shape according to the invention.

- 5 This machine is characterized by a two-armed lever or the like oscillatably mounted on a reciprocatable carriage, the workpiece being secured on one arm of this lever so that it is easily removable, whereas at the end of the other arm 10 a guide roller is arranged which runs on an exchangeable stationary template corresponding to the mean longitudinal section of the workpiece in being exposed to the influence of a spring or weight. Thus, the workpiece is moved in longitudinal direction under uniform pressure along 15 a soft rotating grinding disc according to its protrusions and recesses. The workpiece carrier can be shifted besides in longitudinal direction laterally transversely to the workpiece and, 20 if necessary, it can also be turned after every longitudinal movement so that the workpieces can be moved uniformly past the disc according to their shape and thus mechanically and automatically ground.

With this device the workpiece can be brushed on its entire surface by the grinding disc during a predetermined number of reciprocating movements. By employing a special grinding medium 30 and fibre brushes under moderate grinding pressure which is necessary for preserving the edges and ornamentations, it is possible with this machine for the workpieces to be subjected to sufficient grinding force to remove from the surface 35 thereof stamping burrs, milling marks and dirt.

The machine is extremely simple and cheap to produce and is an equivalent substitute for the complicated and tedious manual labour and also 40 for the expensive special grinding machine, without possessing the disadvantages of the former manufacturing methods.

An embodiment of the invention is illustrated by way of example in the accompanying drawings in which:

45 Fig. 1 shows the device in elevation, partly in section.

Fig. 2 is a similar view of a modified form of construction.

50 Fig. 3 shows a third form of construction.

Figure 4 is a side-view of a workpiece,

Figure 4a is a plan of the same, and

Figure 5 is an end-view thereof.

55 Fig. 6 is a modified construction of the device illustrated in Fig. 1.

Fig. 7 shows the grinding disc frame in end view.

Figs. 8 to 10 show the grinding disc with the workpiece in different positions during the grinding operation.

Fig. 11 is a perspective view of the grinding and polishing machine.

Referring first to Fig. 1, I mention beforehand, in order to facilitate understanding of the invention in general and of this constructional form in particular, that the workpiece 9 is to be moved in three directions, viz. horizontally, vertically, and in a curve, the plane of which stands perpendicularly with respect to the plane of the drawing.

Referring now to the drawings, and first to Fig. 1, a slide 1 is mounted to reciprocate along a suitable guide, not shown, by means such as a crank and a connecting rod, or any other suitable mechanism, not shown, in the direction of the arrow 13—14. The slide is slotted at 3 for the reception of a block. The slot may be horizontal or inclined, straight or curved, and the block is equipped with a pair of handles 4 and 5 for moving it along the slot transversely to the direction indicated by arrow 13—14. A pivot pin 8 on the block supports a double-armed lever 6, 7. A workpiece 9 is secured to the arm 7 of the lever. The end of the other arm 6 is equipped with a roller 10 for cooperation with a template 11 against which the roller 10 is held by a spring 16 anchored on the handle 5 of the block 2. Instead of the spring, a weight, not shown, may obviously be provided. 12 is a tool which is rotated in the direction of the arrow and may be a polishing or grinding wheel or a lap made of soft and resilient material. The material must be so soft that it gives way and adapts itself to the irregularities of the workpiece 9 when the workpiece is forced against it.

As the workpiece 9 moves past below the rotating disc 12, the template 11 causes the uniform maintenance of the grinding pressure. The template 11 corresponds to the actual longitudinal section of the workpiece.

If the guide-slot 3 is curved, the block 2 and the workpiece holder 7, 8 perform a turning movement during the lateral displacement, this turning movement corresponding to the transverse sectional shape of the workpiece 9 to be ground and polished. The lateral displacement of the block 2 is effected by the handles 4, 5 at the end of each stroke of the slide 1 so that the whole transverse section of the workpiece has come into con-

tact with the grinding disc after a number of reciprocating movements of slide 2 depending upon the size of the article. According to the lateral or turning movement as many templates 5 as there are reciprocating movements are placed at the side of the template 11 and merge into one another at the extremities of the movement so that the roller 10 can always run on the corresponding template and the workpiece can be fed 10 past the disc under uniform grinding pressure according to the actual longitudinal section.

Referring now to Fig. 2, the block 2 and the slot 3 in the slide 1 are dispensed with and the pivot 8 of the double-armed lever 6 is secured to the slide. The double-armed lever is divided and the arm 17 which supports the workpiece 9 is mounted to turn in a boss of the arm 6, and is turned by a pair of levers 18 and 19. Spring 16 is anchored to the slide 1. A workpiece holder is 20 secured to the free end of the arm 17 and is crooked so that the projections and recesses of the workpiece are situated on the average in the extension of the axis of the arm 17. Work- 25 pieces, as shown in Figs. 4, 4a and 5 whose cross- section varies but slightly in the longitudinal direction of the workpiece, are ground on the machine illustrated in Fig. 2.

Referring now to Fig. 3, this machine is substantially similar to the one illustrated in Fig. 2 30 but is equipped with a pair of grinding or polishing discs 12 and 30 for tooling both sides of the workpiece 9 at a time. The workpiece is inserted in a fork-shaped holder at the free end of the arm 17 which exposes both sides of the workpiece 35 to the tools.

Fig. 6 shows a construction similar to that of Fig. 3 but simplified by dispensing with the levers 18, 19 and securing the arm 25 in the boss of the 40 arm 6.

The grinding spindle 12 is stationary or its shaft 21 is mounted in a bearing block 26 which is fulcrumed at 22, as shown in Fig. 7. The turning about the fulcrum 22 is carried out in such 45 a manner that at the commencement of the grinding operation the side 23 or 24 of the workpiece 9 is at the highest point of the turning movement of the arm 17, Fig. 3 and assumes a similar opposite position at the end of this movement. Figs. 8 and 10. The grinding disc 12 is inclined to the workpiece 9 in these positions. Thus, an intensive working of the sides of the workpiece will also be attained when the shape thereof deviates considerably from the longitudinal contour in the middle, as the inclined disc runs more easily into the cavities in the workpiece. The top plan views of Figs. 8, 9 and 10 show the working of the left side, of the middle and of the right side respectively.

60 The construction illustrated in Fig. 11 corresponds to that of Fig. 2 and, if two grinding wheels 12 and 20 are used, to that of Fig. 3. The carriage 1 is reciprocated on the carriage guide 27 by a connecting rod 29 and crank disc 28. The pivot pin 8 is journalled in the slide 1, and carries on one end the lever 6 and on its other end the arm 17. The arm 17 is oscillatable in an intermediate bearing 45 about a pin 35 at right angles 65 to the pin 8. The lever 6 carries at its extremity the roller 10 which rolls on the template 11 being continually under the influence of the spring 16, with the result that during the reciprocating movement of the slide 1, the pin 8 carries out a 70 swinging movement according to the shape of

the template. This movement is transmitted to the arm 17 by the intermediate bearing 45 fixed on the pin 8 and by the longitudinal pin 35. The workpiece 9 which always corresponds to the template 11 is fixed on the arm 17 so that it can easily be removed. An angle-shaped stop 48 is 10 adjustably fixed at one end of the arm 17, whereas a sliding stop 49 is fitted on the other end and can be slid up to the workpiece and fixed by 15 means of a screw provided with a handle. Two bearings 39 and 40 are connected to the slide guide 27 and a shaft 36 is oscillatably mounted 20 therein. The shaft 36 receives its movement from a cam, not shown, through the intermediary of a lever 41 and rod 42. A lever 37 is slideable but 25 not rotatable on the shaft 36 and is connected by a rod 38 to the lever 18 on the longitudinal pin 35. The slide 1 has an arm 43 whose outer 30 end is constructed as a fork 44 which slides on the shaft 36 and loosely holds the lever 37.

During the reciprocation of the slide 1 the lever 37 in the fork 44 of the arm 43 is also reciprocated, with the result that the lever 37 is longitudinally shifted and the rotation of the shaft 36 is transmitted by the rod 38 to the lever 18, the longitudinal pin 35 and the arm 17, with the result that the workpiece 9 carries out not only a longitudinal movement but at the same time also a turning movement. By this movement the 35 whole surface of the workpiece 9 is acted upon by the grinding wheel in the course of a number of reciprocating movements. The grinding wheel is rotatably mounted stationary above the workpiece in a bearing 46, which is connected to the machine frame 33. A pulley 47 for the grinding wheel 12, and the disc 28 and rod 41 may be driven from a driving shaft.

The machine frame 33 carries a bearing 40 in which a pin 30 is fitted about which the slide 45 guide 27 is oscillatable at one end. At its other end the slide guide 27 has on its under side a vertical screw spindle 32 rotatable by means of a hand wheel 34. The machine frame 33 has a screw thread corresponding to that of the spindle 45 so that by turning the hand wheel 34 the slide guide 27 and consequently the parts connected therewith, that is the slide 1 with the arm or workpiece holder 17 can be adjusted relatively 50 to the grinding wheel 12. Thus the workpiece can be approached towards or moved away from the grinding wheel as may be rendered necessary by wear of the grinding wheel or the fitting of a smaller or larger grinding wheel.

As in the case of hand work grinding discs made of soft leather, felt or fabric are employed or brushes made of fibre or the like. A mixture of approximately equal quantities of powdered pumices, tripoli and emery powder and oil or 60 water is used as grinding and polishing medium.

For working articles produced in large quantities it is advisable to combine a number of grinding devices to form an aggregate and driven by a common drive. The predetermined number of reciprocations is controlled by a curved guide and clutch so that each device, after having performed its prescribed movements, stops as long as is necessary for re-setting a workpiece. The 65 control preferably takes place so that periodically the devices are stopped, that actually only one is stopped for re-setting, whereas the others continue to work so that a high performance is attained.

I claim:

1. In an automatic grinding and polishing machine, a frame structure, a soft grinding and polishing disc mounted on the frame structure, a carriage movably mounted on the frame structure, a guide mounted on said carriage, and reciprocable therewith relative to said disc and having a curved slot extending substantially parallel to the shaft of said disc, a slide member located 5 in said slot, a two-armed lever mounted between its ends in said slot with one of said arms being in proximity of said disc and adapted to form a holder for a workpiece, a roll at the outer end of the other arm of said lever, a template below 10 said roll, means for holding said roll in constant engagement with said template and means for moving said carriage for shifting movements of said two-armed lever to position the work holding arm of the lever in grinding and polishing association with said disk.
2. In an automatic machine for grinding and polishing oblong workpieces of varying cross section, a frame structure, at least one rotary tool mounted thereon, a reciprocating slide, a two- 15 armed lever pivotally mounted intermediate its ends on said slide, a template which is an exact reproduction of the longitudinal section of the workpiece to be acted upon and of the same length thereof mounted on the frame structure, means 20 for holding one arm of said lever against the template, the other arm of said two-armed lever being pivotally mounted at its inner end on a pin, the axis of which is at right angles to the axis of the two armed lever pivot, said last- 25 named lever arm being in proximity of said tool and adapted to hold a workpiece, means for reciprocating said slide and two-armed lever and means for moving the workpiece holding arm of said lever in a direction at right angles to the 30 longitudinal movement thereof.
3. In an automatic machine for grinding and polishing oblong workpieces of varying cross section, a frame structure, at least one rotary tool mounted thereon, a reciprocating slide mounted 35 on the frame structure, means for reciprocating said slide, there being a slot in said reciprocating slide, the axis of which is at right angles to the direction of movement of said slide, a slide member mounted in said slot, means for reciprocating said slide member in said slot during reciprocable movement of said reciprocating slide, including a two-armed lever fulcrumed on said slide member, a template which is an exact reproduction of the longitudinal section of a work- 40 piece to be acted upon and of the same length thereof mounted on the frame structure, means for holding one arm of said lever against said template, the other arm of said lever being in proximity of said tool and a workpiece support 45 on the last named lever arm.
4. In an automatic machine for grinding and polishing oblong workpieces of varying cross section, a frame structure, at least one rotary tool mounted on the frame structure, a reciprocating 50 slide, means for reciprocating said slide, a two-armed lever fulcrumed on said slide, a template which is an exact reproduction of the longitudinal section of the workpiece to be acted upon and

of the same length thereof mounted on the frame structure, means for holding one arm of said lever against the template, the other arm of said lever being in proximity of said tool and being oscillatably supported at its fulcrumed point on 5 the slide, means for oscillating said arm in timed relation to the reciprocating movements of said slide and a workpiece support on said oscillatable arm.

5. In an automatic machine for grinding and polishing oblong workpieces of varying cross section, a frame structure, two rotary tools, a reciprocating slide on the frame structure, means for reciprocating said slide, a two-armed lever fulcrumed on said slide, a template which is an exact reproduction of the longitudinal section of the workpiece to be acted upon and of the same length thereof mounted on the frame structure, means for holding one arm of said lever against the template, a workpiece support on the other 10 arm of said lever adapted to grip one end of the workpiece to be acted upon and move it between said tools during reciprocation of said slide, the workpiece holding arm having an oscillatable mounting at its fulcrum connection with said slide and means for oscillating said work holding arm in timed relation to the reciprocating movement of said slide.

6. A machine for grinding and polishing oblong workpieces as set forth in claim 5, characterized 30 by a bearing block carrying said tool and adapted to be oscillated in a horizontal plane to adjust the tool to the varying cross-sectional shapes of workpieces presented thereto.

7. In an automatic grinding and polishing machine of the class described, a frame structure, a slide mounted thereon, means for reciprocating said slide, a rotatable bearing in said slide having its longitudinal axis at right angles to the direction of movement of said slide, a lever arm 35 carried by one end of said bearing, a template on the frame structure, means for holding said arm in constant engagement therewith during reciprocatory movements of said slide, a work-holding lever arm pivotally mounted at its inner end 40 to the other end of said bearing on an axis at right angles to the axis of said bearing and means for effecting pivotal movements of the workpiece holding arm in timed relation and a rotary tool mounted on the frame structure in proximity of 45 said work-holding arm.

8. In an automatic grinding and polishing machine, a frame, a soft grinding and polishing disk mounted on said frame, a carriage movable on the frame, an axle on the carriage, a two-armed 55 lever journaled between its ends on said axle, a roller at the free end of one arm, a template plate on the frame engaged by said roller during movements of said carriage, a pivotal connection between the other arm of the two-armed lever and said axle, a workpiece adapted to be supported on the pivotally mounted arm of said two-armed lever for engagement by said grinding and polishing disk, means for moving the carriage and independent means for pivotally moving the work 60 supporting arm of said two-armed lever.
